UNITED STATES PATENT OFFICE.

HOWARD AINSLIE BURSON, OF PITTSBURGH, PENNSYLVANIA.

BOX-LID OPENER.

1,182,346.

Specification of Letters Patent. Patented May 9, 1916.

Application filed December 9, 1914. Serial No. 876,228.

To all whom it may concern:

Be it known that I, HOWARD AINSLIE BURSON, a citizen of the United States of America, residing at Pittsburgh, in the county of Allegheny and State of Pennsylvania, have invented certain new and useful Improvements in Box-Lid Openers, of which the following is a specification, reference being had therein to the accompanying drawing.

10 This invention relates to a box lid opener and has for its object to provide means, in a manner as hereinafter set forth, carried by the body portion of the box, and capable of being shifted to engage the edge of the lid, 15 for the purpose of prying the lid off from the body portion.

Further objects of the invention are to provide a device for the purpose set forth which is simple in its construction and arrangement, strong, durable, efficient and convenient in its use, and inexpensive.

With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modification 30 can be resorted to which come within the scope of the claim hereunto appended.

In the drawings wherein like reference characters denote corresponding parts throughout the several views:—Figure 1 is an elevation of a box having a lid showing the adaptation therewith of a lid opener in accordance with this invention. Fig. 2 is a top view of a box, broken away, showing a lid opener in accordance with this invention in full and in dotted lines. Fig. 3 is a transverse sectional view of a box having a lid and further showing in connection therewith a box lid opener in accordance with this invention.

45 Referring to the drawings in detail 1 denotes the body portion of a box or a receptacle, by way of example a circular box or receptacle adapted to contain paste or polish, and said body portion is open at its top.

50 The reference character 2 denotes a lid for closing the open top of the body portion 1 and the rim of the lid is indicated at 3, and which terminates in a lateral extending flange 4. The body portion 1 has an out-

wardly projecting bead 5, against which 55 abuts the rim 3 of the lid 2 when the latter is mounted in position of the body portion 1 to close the open top of the latter.

Connected to the body portion 1, below the bead 5, is a pin 6, which constitutes a 60 pivot and has its outer end provided with a head 7. The pin 6 projects laterally from the body portion 1, and has pivotally mounted thereon the body portion 8 of a lid opener and said body portion 8 is semi-circular in 65 contour and is mounted, near its top, upon the pin 6.

Projecting outward from the top edge of the body portion 8 of a lid opener and extending at right angles with respect thereto is an arm 9, which terminates in a vertically disposed handle 10. The latter has an outwardly projecting right angular lug 11, which extends in a plane at right angles with respect to the arm 9. The arm 9 offsets the 75 handle of the rim 3 of the lid 2.

By shifting the body portion 8 upon its pivot the edge thereof will engage in the lower end of the rim 3 and pry the lid 2 from off the body portion 1, or conveniently 80 shift the lid 3 from off the body portion 1 so that the lid can be removed by hand.

What I claim is:—

The combination with a box having an uninterrupted circumferential bead and a 85 lid therefor also having an uninterrupted circumferential marginal flange extending laterally beyond the aforesaid bead, when said lid is in position on the box; of a semi-circular shaped lid raiser pivoted adjacent 90 its top end to said box below the bead thereon and adapted to exert an upward pressure on said lid, said lid raiser being so pivoted as to normally lie with the straight side thereof parallel with the bottom of the box, 95 and an integral handle formed on said lid raiser and extending upwardly and outwardly with respect to the pivoted end thereof, whereby to form a clearance for the aforesaid bead and flange when the handle 100 is swung downwardly to raise said lid.

In testimony whereof I affix my signature in presence of two witnesses.

HOWARD AINSLIE BURSON.
